WASHING MACHINE

2 Sheets-Sheet 2

UNITED STATES PATENT OFFICE.

OSCAR E. STOKES, OF STREATOR, ILLINOIS.

WASHING MACHINE.

Application filed December 9, 1922. Serial No. 605,759.

The invention relates to washing machines and more particularly that class of washing machines in which the tank or container is mounted and adapted to oscillate on a horizontal axis, supported by a suitable frame. The primary object of the invention is to improve the connections between the source of power for operating the machine and the oscillating container or tank.

10 A further object of the invention is to provide a connection between the source of power and the oscillating container or tank of such character and construction that the tank may be readily and instantly thrown into and out of operative engagement with the source of power.

20 A further object of the invention is to so construct the connecting means between the source of power and the oscillating tank that when the tank is thrown out of operative engagement with the source of power that the tank will be automatically locked against oscillating movement.

25 A further object of the invention is to so construct the connecting means between the oscillating tank and source of power that when the connecting means is thrown into the operative position the tank will be automatically secured in engagement with the connecting means.

30 Other objects of the invention will appear from the following description which is directed to the preferred embodiment of the invention as shown in the drawings forming a part of the specification, the novel features thereof being more particularly pointed out in the appended claims.

35 In the drawings Fig. 1 is an end elevation of the improved washing machine showing a wringer combined therewith.

40 Fig. 2 is a horizontal section taken on line 2-2 of Fig. 1 looking in the direction of the arrows.

45 Fig. 3 is a horizontal sectional view taken on line 3-3 of Fig. 1 looking in the direction of the arrows.

Fig. 4 is an enlarged end elevation view of the structure shown in Fig. 1, the wringer and its connections being omitted.

Fig. 5 is a vertical sectional view taken 50 on line 5-5 of Fig. 4.

Fig. 6 is a horizontal sectional view taken on line 6-6 of Fig. 4.

Fig. 7 is a transverse sectional view of the container or tank showing the improved 55 draining means.

In the construction of the improved washing machine, a suitable rectangular supporting frame designated generally by reference character 10, having suitable supporting standards 11 and 12, is provided for the support of the container or tank 13, it being understood that there are four of these standards provided, one at each corner of the rectangular frame. The supporting standards 60

11 and 12 are provided with appropriate braces 14 extending therebetween. The supporting frame 10 is provided with shelf 15 adjacent the bottom thereof for the support of motor 16, and gear housing 17 is secured 70 to braces 14 and leg 12. Power shaft 18 of motor 16 is connected at its outer end to driving shaft 19 by any suitable torsion coupling as by flexible torsion sleeve 20, for example, as clearly shown in Fig. 2 of the 75 drawing. Driving shaft 19 is journaled in the side walls of housing 17 as at 21, 22 and has rotatably mounted thereon gear wheel 23 meshing with gear wheel 24 affixed to

80 shaft 25 journaled in the side walls of housing 17 as at 26, 27. Shaft 25 also has non-rotatably mounted thereon gear wheel 28 in mesh with large gear wheel 29 which is affixed to shaft 30 journaled in the side walls 85 of the housing 17 as at 31, 32. Shaft 30 has affixed to its outer end crank arm 33 rotatably related to pitman 35 through the medium of pin 36. Pitman 35 is pivotally related to rocking arm 37, as at 38, said arm being supported by stub shaft 39 secured to 90 frame 10 as at 10^a for imparting an oscillating or rocking movement to container or tank 13 in a manner to be hereinafter described. Tank 13 is pivotally supported by the inner end of stub shaft 39 as at 39^a.

95 Rock shaft 41 has affixed to the inner end thereof clutch shifting fork member 42 which terminates at its upper extremity in

spaced apart prongs or shifter members 43, 44 for shifting clutch 45.

The clutch member 45 is provided with two pairs of oppositely disposed arms 46, 47 and 48, 49, respectively. The arms 46 and 48 are spaced apart from and in transverse alignment with the respective corresponding arms 47 and 49 respectively. Extending concentrically of the axis of the clutch member 45 is a recess or channel as shown at 50—51. Mounted in the channel 50—51 and on the opposite sides of the clutch member are studs 52 and 53 which are formed integrally with the shifter prongs 43 and 44. The rocking shaft 41 is provided at its outer extremity with an operating lever 54 for rocking the shaft 41 to throw the shifter member 42. Mounted between the corresponding arms 46, 47 and 48, 49 respectively, are tubular blocks 55 and 56 respectively. These collars 55 and 56 are held in their respective positions by clutch pins 57 and 58 which extend through their respective collars and co-operating arms respectively, as shown in Fig. 3. The pins 57 and 58 are secured against longitudinal displacement by transverse locking pins 59 and 60, respectively. The clutch pins 57 and 58 extend beyond the inner face of the arms 46 and 48 respectively and are adapted to have their inner ends engage sockets 61 and 62 in plate 63 secured to the side wall of the container or tank 13 to oscillate the tank when the clutch member 45 is moved on the sleeve 63^a into position shown in Fig. 3 by the operation of the rocking shaft 41. The outer ends of the locking pins pass through bores 64, 65 in rocking arm 37 with their outer extremities flush with the outer face of rocking arm 37 when the clutch is moved inwardly into engagement with plate 63, the locking pins being constantly engaged by rocking arm 37 as clearly shown in Fig. 3. The lower portion of the clutch shifting member 42 is formed substantially in the shape of the letter Y having branches 66 and 67. To the lower extremity of branch 67 is pivotally related extension arm 68 at its upper end and having its lower end passing through pivotal member 69 and adapted to have reciprocal movement with relation thereto. The arms 67 and 68 form a toggle link arrangement whereby the shifter member 42 may be locked in either of its extreme positions. Pivotal member 69 is journaled in bracket 70 of frame 10. Around extension arm 68 is placed helical spring 71 which is adapted to exert an upward pressure on extension arm 68 and hold the clutch shifting member 42 at the limit of its movement in either direction when moved past its center with relation to pivotal member 69. Branch 66 of the clutch shifting member 42 carries at its lower extremity shoe 72 having curved or turned ends 88 for depressing spring actuated locking pin 74 carried by the

bottom portion of the container frame 75 for locking the container or tank to the frame 10 against oscillating movement. The shoe 72 is provided at the approximate center thereof with socket 73 for the engagement therein, under spring tension, of the locking pin 74 which is held yieldingly in position to engage the socket by a spring 74^a surrounding the pin and co-operating with the bracket 74^b.

Shaft 30 has beveled gear 76 for cooperating with suitable gears (not shown) for imparting rotary movement to shaft 77 for operating wringer 78.

In forming the container or tank the bottom is carried inwardly and upwardly at the center thereof forming a baffle or deflector 79 substantially describing in cross section the letter U in inverted position, and the side walls of the tank are carried downwardly and inwardly at their upper portion as at 80 thus forming a deflector at the top portion of the tank which in conjunction with the deflector 79 at the bottom thereof causes water in the tank to substantially describe the figure 8 in its movement when the tank is oscillated. Opening 81 is provided for access to the tank and cover or lid 82 is provided for closing the opening. The formation of deflector 79, as described, in the bottom of the tank results in producing depending lobes 83 and 84 extending longitudinally of the tank, one of such lobes being on each side of the median line of the bottom of the tank. Drain conduit 85 connecting the lowermost portions of the lobes 83 and 84 has outlet pipe 86 for draining the container. Outlet pipe 86 is provided with a suitable cut-off valve 87.

Gear 23 is frictionally held between collars 89 and 90 under tension of spring 91 coiled around clutch sleeve 91' thereby providing a slip connection between gear 23 and shaft 19 which will permit of the drive shaft 19 rotating independently of gear 23 when a load is suddenly transmitted thereto, which provides for the gradual picking up of the load by gear 23 and preventing the burning out or other damage to the motor. Collar 92 carried by clutch sleeve 91' is affixed to drive shaft 19 by pin 93 and adapted to rotate therewith.

In the operation of the improved washing machine herein described the clutch 45 is moved outwardly by the operating lever 54 rocking the clutch shifting member 42, disengaging locking pins 57 and 58 from plate 63, which will simultaneously lock the container or tank, when in midposition, to the frame 10 through the medium of spring actuated pin 74 engaging socket 73 in shoe 72 carried by the lower extremity of branch 66 of clutch shifting member 42. The container or tank 13 being thus held in upright position and against oscillating movement, wa-

ter or other washing fluid in sufficient quantity is introduced into the tank through opening 81 when the articles to be washed may be introduced in the tank and submerged in the water or other washing fluid when the tank is closed by cover 82. The motor may now be started and the clutch shifted in the reverse direction by the manipulation of operating lever 54 and the locking pins 57 and 58 thrown into engagement with slots 61 and 62 of plate 63 when the container or tank 13 will be caused to rock in unison with rocking arm 37, the container or tank having been released from its locking engagement with shoe 72 simultaneously with the shifting of the clutch. Any tendency toward sudden strain on the motor will be absorbed by torsion coupling 20, and by a preferred frictional connection between gear 23 and shaft 19 so that in the event of an overload the motor will not be stalled and injured.

Having thus described my invention what I claim is:

1. In a washing machine, the combination with a supporting frame, of a tank oscillatably supported by said frame, a rocking arm supported by said frame, a movable clutch in constant engagement with the rocking arm and adapted to be moved into and out of engagement with the tank, a lever pivoted to said frame for controlling said clutch, means formed integrally with said lever for locking said tank against movement and a spring for actuating said lever on its pivot for holding the clutch in its engaging and disengaging position with relation to the tank.

2. In a washing machine, the combination with a supporting frame of a tank pivotally supported by said frame, a rocking arm supported by the frame, a clutch device positioned adjacent the pivot of said tank and in constant engagement with the rocking arm, said clutch device being movable axially with respect to said arm and adapted to move into engagement with the tank, a lever for moving the clutch, and means forming a toggle link connection with said lever for securing the clutch device in inoperative position with relation to the tank.

3. In a washing machine, the combination with a supporting frame of a tank pivotally supported by the frame, a rocking arm supported by the frame, a clutch device mounted concentrically with the axis of said tank and in constant engagement with the rocking arm and adapted to move into engagement with the tank, a lever for moving the clutch, tank securing means formed integrally with said lever, and means forming a spring actuated toggle link connection with said lever for securing the clutch device and said tank securing means in operative or inoperative position.

4. In a washing machine having a frame, a tank pivotally supported by the frame to have oscillatory movement thereon, the combination of a rocking arm pivotally related to the frame, a lever pivotally supported by the frame for locking the tank to the rocking arm, and means for locking the tank against oscillatory movement in relation to the frame, comprising a shoe carried by said lever and a spring controlled detent carried by the tank, there being an opening formed in the surface of said shoe for engagement with said detent on the tank. 75

5. In a washing machine comprising a frame and an oscillatory tank supported thereby, the combination with a stud supported by said frame, of an actuating lever provided with a perforated hub portion pivotally mounted on said stud adjacent the frame, power transmitting mechanism pivotally connected with one end of said lever for imparting oscillatory movements thereto, a plate secured to said tank and being provided near the center portion of the exposed face thereof with a sleeve adapted to telescope over the end of said stud into approximate contact with said actuating lever, an oscillating clutch member mounted to have a bearing on said sleeve whereby to have a sliding movement on said sleeve between said plate and said actuating lever, a pin affixed to said clutch member, said pin being arranged to have extensions at each side of said clutch member, one extension of said pin being adapted to engage the said actuating lever and the other extension being adapted to engage with the said plate on the tank, and hand operated mechanism for shifting the said clutch member to cause the said pin thereon to engage or disengage the said plate on the tank in a manner to permit the said tank to be oscillated or to remain idle at the will of the operator. 95

6. In a washing machine comprising a frame and an oscillatory tank supported thereby, the combination with a stud supported by said frame, of an actuating lever provided with a perforated hub portion pivotally mounted on said stud adjacent the frame, power transmitting mechanism pivotally connected with one end of said lever for imparting oscillatory movements thereto, a plate secured to said tank and being provided near the center portion of the exposed face thereof with a sleeve adapted to telescope over the end of said stud into approximate contact with said actuating lever, an oscillating clutch member mounted to have a bearing on said sleeve whereby to have a sliding movement on said sleeve between said plate and said actuating lever, two pins affixed to the clutch member, said pins being mounted at the opposite ends of the clutch member and arranged to have ex- 110 115 120 125 130

tensions at each side of said clutch member, one extension of each pin being adapted to engage the said actuating lever and the other extension being adapted to engage with the said plate on the tank, and hand operated mechanism for shifting the said clutch member to cause the said pins thereon to engage or disengage the said plate on the

tank in a manner to permit the said tank to be oscillated or to remain idle at the will of the operator. 10

In testimony whereof I have signed my name to this specification on this 5th day of Dec. A. D. 1922.

OSCAR E. STOKES.
